(57) CLAIM

The ornamental design for a golf club shaft, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a golf club shaft showing our new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof;

FIG. 8 is an enlarged fragmentary front view taken along line 8—8 and in the direction of arrows in FIG. 2;

FIG. 9 is an enlarged fragmentary rear view taken along line 9—9 and in the direction of arrows in FIG. 3;

FIG. 10 is an enlarged fragmentary top plan view taken along line 10—10 and in the direction of arrows in FIG. 4;

FIG. 11 is an enlarged fragmentary bottom plan view taken along line 11—11 and in the direction of arrows in FIG. 5; and,

FIG. 12 is a view of the pattern shown on the golf club shaft of FIG. 1 projected onto a flat surface.

The combination of the red, black and silver color shown in the photos is claimed.
